UNITED STATES PATENT OFFICE

105,353

DESIGN FOR AN AUTOMOBILE EMBLEM PLATE

Leroy E. Wright, Oxford, N. J.

Application May 27, 1936, Serial No. 62,855

Term of patent 7 years

To all whom it may concern:

Be it known that I, Leroy E. Wright, a citizen of the United States, residing at Oxford, in the county of Warren and State of New Jersey, have invented a new, original, and ornamental Design for an Automobile Emblem Plate, of which the following is a specification, reference being had to the accompanying drawing, forming part thereof.

I claim:

The ornamental design for an automobile emblem plate, substantially as shown.

LEROY E. WRIGHT.
